UNITED STATES PATENT OFFICE.

ANDERS BORCH RECK, OF HELLERUP, DENMARK.

MAGAZINE-BOILER.

No. 851,030.

Specification of Letters Patent.

Patented April 23, 1907.

Application filed July 26, 1906. Serial No. 327,839.

To all whom it may concern:

Be it known that I, ANDERS BORCH RECK, captain, a citizen of Denmark, residing at Christiansvej 16, Hellerup, Denmark, have 5 invented new and useful Improvements in Furnaces for Magazine-Boilers, of which the following is a specification.

The object of my invention is to provide means for maintaining in boilers with a 10 magazine for fuel a constant combustion with a high efficiency without the accumulation of the incombustible part of the fuel diminishing the rate of combustion during the periods where the boiler is left alone without being attended to. The accompanying 15 drawings show examples of application of my invention to different kind of boilers.

Figure 1 is a longitudinal vertical section through a sectional cast-iron boiler, being 20 especially adapted for non-bituminous coal or coke. Fig. 2 is a horizontal section of the same boiler. Fig. 3 is a longitudinal vertical section through the fore part of a cast-iron sectional boiler especially adapted for bituminous coal. Fig. 4 is a horizontal section 25 through the boiler shown in Fig. 3. Fig. 5 is a longitudinal vertical section through a steel or wrought-iron boiler especially adapted to bituminous coal and with the grate inside the 30 boiler. Fig. 6 is a horizontal section through the same boiler. Fig. 7 is a longitudinal vertical section through a steel or wrought-iron boiler also adapted for bituminous coal, but with the grate outside the boiler, connections 35 being provided for the circulation of the water from the boiler through the water-chambers inclosing the grate and the pipes *e* and *c*, which connect said water-chambers with each other. Fig. 8 is a horizontal section 40 through the same boiler.

In all figures the parts that serve to the same purposes are designated by the same letters.

It will now be seen that in all figures the 45 grate of the boiler is shown divided in two parts, an upper part that is vertical and a lower part that is sloping down against the hind support of the grate in order to keep a uniform thickness of the layer of fuel on the 50 grate and in order to allow the ashes formed by the combustion to be pushed to the hind part of the grate by the fresh fuel sinking down from the magazine *g*, such ashes collecting in the hind part of the ash-pit that is open 55 to the combustion-chamber.

The upper vertical part of the grate is in all forms of the boilers shown formed of horizontal tubes *c*, said tubes being connected with the hollow side walls of the furnace in such a manner that the water of the boiler 60 can circulate through the tubes.

The lower sloping part of the grate is in all forms of the boilers shown formed of ordinary grate-bars *d*, resting on tubes *e*, wherein the water from the boiler circulates in the same 65 manner as in the tubes *c*. The grate-bars *d* are protected against being too hot partly by contact with the tubes *e* and partly by radiation to the side walls of the furnace, the water of the boiler circulating through said side walls 70 and tubes, as explained above. In the boilers shown in the Figs. 1-6 the grate-bars *d* radiate heat even to the bottom of the ash-pit, said bottom being hollow and its interior space being filled with water and communicating with or forming part of the boiler. 75

In the cast-iron sectional boilers shown in Figs. 1, 2, 3, and 4 a strong circulation of water can be produced through the horizontal tubes *c* and *e*, through which the water-spaces of the two side walls of the furnace communicate with each other. To attain this end, the front section of the boiler is divided by a vertical partition *f*, (shown in Fig. 2,) one side of said front section communicating with the section of the boiler next to it near its bottom, the other side of the front section being connected to the next section near its top. When the water is heated in one side of the front section of the 80 boiler by the action of the fire, the result will be that such water will rise and pass through the top connection to the next section of the boiler, and fresh water will be drawn from the bottom of the said next section of the 85 boiler to the other side of the front section and from there through the tubes *c* and *e*. It will be seen that in this manner the front section is really divided by the vertical partition *f* into two separate water-chambers, connected to each other only through the pipes *c* and *e*. A similar strong circulation through the tubes *c* and *e* can be produced in the 90 boiler shown in Figs. 7 and 8. Here the furnace of the boiler is inclosed on its sides 95 by two water-chambers connected by the tubes *c* and *e*. One of the said water-chambers communicates with the boiler at its bottom only and the other at its top only. Thus the heating of the water in the water-cham- 100 105 110

bers inclosing the furnace will produce the same circulation of water as described for the boilers shown in Figs. 1-4.

In all the boilers shown in the figures a vertical fuel-magazine *g* surmounts the sloping part of the grate. As the fuel is consumed on the grate by the combustion fresh fuel will sink down from the magazine, taking the place of the consumed fuel and pushing (by its weight) the incombustible part of the fuel (ashes and clinkers) down along the sloping grate to the hind part of the ash-pit, that is open to the combustion-chamber *h*.

It will be seen that the hind part of the ash-pit is large enough to hold a considerable quantity of ashes, and consequently these boilers can be run many hours before the ashes will collect to such an extent that the air-spaces between the slanting grate-bars will be clogged up, and even then combustion can go on, the air-spaces between the tubes *c* of the vertical part of the grate giving sufficient access to the air. It will further be seen that since the hindmost of the two pipes *e*, that support the slanting grate-bars, is a tube cooled by the water of the boiler no harm can be done to the said pipe even in case the attendant when clearing the ash-pit for ashes takes out so much that some burning fuel comes down below the pipe.

It will be seen that in all forms of boilers shown in the figures the fuel-magazine is quite open to the combustion-chamber *h*, no water-cooled surfaces separating the fuel-magazine from the combustion-chamber and preventing the products of the combustion from attaining such a high temperature that is the most effective for a good combustion of the gases in the combustion-chamber. Further, it will be seen that in all forms of boilers shown in the figures an air-channel *r* is covering the whole front of the boiler. The object of this channel *r* is that the air destined to pass to the fuel through the grate (the primary air) may be heated to as high a temperature as possible. The air passes into the upper part of the channel *r*, where the entrance of the air is marked by arrows and is led down to the ash-pit, a plate 1 forming the inner wall of the lower part of the air-channel, the front door *k* of the boiler forming the outer wall. While the air passes through channel *r* it takes up heat that else would be radiated and lost from the front of the boiler, whereas now the heating of the air before it goes through the grate contributes a great deal to a good combustion in the furnace of the boiler.

If the boilers, as the three boilers shown in the Figs. 3-8, are destined for bituminous coal, the combustion in the combustion-chamber *h* is improved by introduction into said chamber of highly-heated air direct from outside (secondary air.)

65 In Fig. 4 will be seen air-channels *o* for the

secondary air rising along the inner walls of the water-chambers that inclose the furnace. These air-channels *o* have openings to the outside air through the outer walls of the water-chambers and unite in a horizontal channel *o* over the combustion-chamber *h*, as shown in Fig. 3. The vertical parts of the air-channel *o* are closed to the furnace side by fire-bricks *p*, (see Fig. 4,) and the horizontal part of the channel is separated from the combustion-chamber by a large block of fire-brick *q*, that will be highly heated by the gases burning in the combustion-chamber. As shown in Fig. 3 and Fig. 4, said block of fire-brick *q* is perforated with holes, through which the secondary air finds its way from the channel *o* to the combustion-chamber. Similar air-channels *o* and blocks of fire-brick *q* are shown in Figs. 6 and 7 and serve for the same purpose as described for Fig. 3 and Fig. 4—viz., to give access for highly-heated air direct into the combustion-chamber when bituminous coal is to be used for the boilers.

Having thus described my invention, what I claim as new, and desire to secure by Letters Patent, is—

1. In a boiler for steam or water the combination of a fuel-magazine, a grate divided into an upper vertical part and a lower sloping part situated below the fuel-magazine and a combustion-chamber with water-cooled walls open as well against the fuel-magazine as against the ash-pit behind the sloping part of the grate.

2. In a boiler for steam or water the combination of a fuel-magazine, a grate divided into an upper vertical part and a lower sloping part situated below the fuel-magazine, a combustion-chamber with water-cooled walls open as well against the fuel-magazine as against the ash-pit behind the sloping part of the grate and an air-channel with access for the outside air, said channel covering the front of the boiler and opening into the ash-pit.

3. In a boiler for steam or water the combination of a fuel-magazine, a grate divided into an upper vertical part and a lower sloping part situated below the fuel-magazine, a combustion-chamber with water-cooled walls open as well against the fuel-magazine as against the ash-pit behind the sloping part of the grate, and an air-channel opening into the said combustion-chamber through a fire-brick lining over said chamber.

4. In a boiler for steam or water the combination of a fuel-magazine, a grate divided into an upper vertical part and a lower sloping part situated below the fuel-magazine, a combustion-chamber with water-cooled walls open as well against the fuel-magazine as against the ash-pit behind the sloping part of the grate, and horizontal pipes between said water-cooled chambers, said

pipes forming the vertical part of the grate and the supports of the sloping part of the grate, and said water-cooled chambers being connected to the boiler one at its bottom and 5 the other at its top.

5. In a boiler for steam or water the combination of a fuel-magazine, a grate divided into an upper vertical part and a lower sloping part situated below the fuel-magazine 10 and sloping down against a horizontal pipe supporting the back end of the grate and having its ends inserted into the inner walls

of the boiler or the inner walls of water-cooled chambers connected to the boiler, and a combustion-chamber open as well against the fuel-magazine as against the ash-pit behind the said pipe supporting the grate. 15

In testimony whereof I have signed my name to this specification in the presence of two subscribing witnesses.

ANDERS BORCH RECK.
